DESIGN FOR A SOAP HOLDER OR SIMILAR ARTICLE

Roy S. Sanford, Oakville, Conn., assignor to The Autoyre Company, Incorporated, Oakville, Conn., a corporation of Connecticut

Application February 28, 1938, Serial No. 75,473

Term of patent 7 years

To all whom it may concern:

Be it known that I, Roy S. Sanford, a citizen of the United States, residing at Oakville, in the county of Litchfield and State of Connecticut, have invented a new, original, and ornamental Design for a Soap Holder or Similar Article, of which the following is a specification, reference being had to the accompanying drawing, forming a part thereof.

Figure 1 is a top plan view of the soap holder or similar article showing my new design;

Fig. 2 is a front elevational view of Fig. 1; and Fig. 3 is an end elevational view of Fig. 2.

The dominant features of the soap holder or similar article are the provision of a substantially rectangular shape with truncated corners and with a substantially flat bottom having side walls extending upwardly therefrom in two annular directions to a peripheral bead of polygonal cross section, the base having raised portions conforming substantially in a direction to the periphery of the receptacle with openings in the side walls of polygonal conformation, as shown.

I claim:

The ornamental design for a soap holder or similar article, substantially as shown and described.

ROY S. SANFORD.
